Attorney

UNITED STATES PATENT OFFICE

WILLIAM B. WANSOR, OF LOCUST VALLEY, NEW YORK

CIGARETTE HOLDER

Application filed March 10, 1931. Serial No. 521,575.

This invention relates generally to smokers' articles and has particular reference to a safety holder for cigarettes or the like.

Among the objects of the present invention are to provide a cigarette holder having means for holding a cigarette in position to be smoked and at the same time prevent any ashes from falling on the floor and sparks from dropping, thus avoiding any danger of fire.

A further object proposes the use of a compact device in which various accessories such as matches may be conveniently carried, in addition to the use of a container for ashes.

To the attainment of these and other objects which will appear as the description proceeds, reference may be made to the accompanying drawings, in which:—

Fig. 1 is a perspective view of the device;

Fig. 2 is a sectional elevation thereof;

Fig. 3 is an end elevation;

Fig. 4 is a sectional elevation on the line 4—4 of Fig. 2; and

Fig. 5 is a detailed view of the cigarette holding element.

Referring specifically to the drawings in which like reference numerals represent like parts, it will be observed that the device consists of a body 10 having a mouth piece 11, removably attached as at 12 to the body. Supported within the upper portion of the body, and in alignment with the mouth piece is a cage or grate 13 adapted to support a cigarette C. The cage will preferably be held in position by means of ears 14 which may be riveted or otherwise suitably connected as at 15 to the holder 10. A clean-out door 16 for the removal of ashes may be hinged at the bottom of the holder and a similar door 17 for the reception of burned matches may be located at the forward portion of the holder. These doors may be hingedly attached to the body portion 10 and provided with spring latches 18 and 19 respectively to hold same closed.

The top of the holder may be provided with a hinged closure 20 having a latch 21. The forward end of this closure preferably consists of a downwardly extending perforated flange 22 having a spring pressed closure por-

tion 23 depending therefrom. The perforations 22 act as draft holes when the cigarette is being smoked and the closure 23 may be opened to permit lighting of the cigarette.

A chain or cord 24 is desirably connected to the holder to function as a neck chain or vest chain when the device is not being used.

Having thus described the invention the use and operation thereof will be readily apparent, the lid 20 is raised and a cigarette inserted in the cage or grate 13, the lid being closed to retain same in position. The cigarette is then lighted after opening the closure 23, and the burned match placed in the body 10 through the opening 17. As the cigarette burns any ashes or sparks therefrom will drop into the interior of the body 10 as indicated by the ashes and matches 25 in Fig. 4.

Ordinarily the cigarette will burn completely to its end due to the fact that it is resting on an open grate, but obviously if same does not burn completely it can be removed at any time by raising the lid 20.

It will be evident that variations in the above structure and in the shape thereof are possible, for example, either of the clean-out doors 16 or the opening for matches at 17 or both may be omitted, in which latter event ashes may be removed by turning the holder upside down assuming, however, that no matches have been placed within the holder.

It is also conceivable that the closure or lid 20 may be omitted and the cigarette held in place in the cage in any conventional manner, with its butt-end adjacent the mouth-piece 11. It is also contemplated that the structure may be adapted to the use of cigars or tobacco cartridges thus forming in effect a variation of pipe.

One modification of the foregoing structure which might readily fall within the scope of the present invention would be the formation of a compartment adjacent the opening 17, in which matches, either live or burnt might be placed, and thus the débris in the body 10 would be confined solely to tobacco ashes. If live matches are carried in such a compartment, a scratcher therefor could be secured as by pasting to the side of the body 10.

It is clear that the entire device may be made of any material, light in weight so that the entire structure will weigh no more and be no larger in size than a conventional pipe.

5 Having thus described my invention, what I claim as new and desire to secure by Letters Patent of the United States, is:—

1. A device of the character described, comprising a body member having a recess to receive ashes, a grate for retaining a cigarette thereabove, and a mouth-piece in alignment with said grate.

10 2. A device of the character described, comprising a body member having a recess to receive ashes, a grate for retaining a cigarette thereabove, and a mouth-piece in alignment with said grate, and a closure for said recess disposed above said grate thereby to retain the cigarette in position.

15 3. A device of the character described, comprising a body member having a recess to receive ashes, a grate for retaining a cigarette thereabove, and a mouth-piece in alignment with said grate, and a closure for said recess disposed above said grate thereby to retain the cigarette in position, and a pivoted closure at the outer end of said recess affording access to said cigarette, for lighting purposes.

20 4. A device of the character described, comprising a body member having a recess to receive ashes, a grate for retaining a cigarette thereabove, and a mouth-piece in alignment with said grate, and a clean out door in said body member through which ashes from

25 said body member may be removed.

5. A device of the character described, comprising a hollow body member, a closure extending along the top thereof, a grate extending within the top portion thereof below said closure, a mouth-piece at one end of said body in alignment with said grate and a perforated wall at the other end of said body in alignment with said grate and mouth-piece, the lower portion of said body member forming a receptacle for ashes, and a clean-out door at the bottom of said member.

30 6. A device of the character described, comprising a hollow body member, a closure extending along the top thereof, a grate extending within the top portion thereof below said closure, a mouth-piece at one end of said body in alignment with said grate and a perforated wall at the other end of said body in alignment with said grate and mouth-piece, the lower portion of said body member forming a receptacle for ashes, said member below said perforated wall having an opening for the reception of matches.

35 7. A device of the character described, comprising a hollow body member, a closure extending along the top thereof, a grate extending within the top portion thereof below said closure, a mouth-piece at one end of said body in alignment with said grate and a perforated wall at the other end of said

body in alignment with said grate and mouth-piece, the lower portion of said body member forming a receptacle for ashes, said member below said perforated wall having an opening for the reception of matches and a clean-out door at the bottom of said member.

8. A device of the character described, comprising a hollow body member, a closure extending along the top thereof, a grate extending within the top portion thereof below said closure, a mouth-piece at one end of said body in alignment with said grate and a perforated wall at the other end of said body in alignment with said grate and mouth-piece, and a pivoted closure at the outer end of said body member affording access to said cigarette below said perforations for lighting purposes.

9. A device of the character described, comprising a hollow body member having an opening for the reception of cigarettes at the top thereof, means to support the cigarette therein, a closure for said opening, a mouth-piece on said member communicating with the interior thereof, and means having an opening for intake of air to said member, a pivoted closure at the outer end of said body member affording access to said cigarette for lighting purposes, the portion of said member below said cigarette supporting means forming a receptacle for ashes.

In testimony whereof I affix my signature.

WILLIAM B. WANSOR.
